UNITED STATES PATENT OFFICE.

ELBRIDGE WHEELER, OF BOSTON, MASSACHUSETTS, ASSIGNOR TO HIMSELF,
WARE B. GAY, AND GEORGE W. GOGIN, TRUSTEES, ALL OF SAME PLACE.

MOLD OR APPARATUS FOR CASTING COMPOUND INGOTS.

SPECIFICATION forming part of Letters Patent No. 363,032, dated May 17, 1887.

Application filed April 4, 1884. Serial No. 126,669. (No model.)

To all whom it may concern:

Be it known that I, ELBRIDGE WHEELER, of Boston, county of Suffolk, State of Massachusetts, have invented an Improvement in
5 Molds or Apparatus for Casting One Metal Around Another, of which the following description, in connection with the accompanying drawings, is a specification, like letters on the drawings representing like parts.

10 My invention has for its object to cast in a compound mold two distinct grades of metal for the production of an ingot which shall be composed at one part of a hard and at another part of softer metal, preferably steel, the hard steel being either outside or inside, according to the use to be made of the ingot. To accomplish this desired result, I have devised a compound mold, or a mold within a mold, the inner mold taking up in the outer mold substantially the space which will ultimately be taken up in the ingot by the second of the two metals to be poured to form the said ingot.

15 In my invention for producing a compound ingot from different metals, the first metal to be poured is poured into the inner mold, while the latter is contained in the outer mold, and the second metal to be poured is poured into the space left in the outer mold by withdrawing from it the inner mold after the first cast 20 or casting has been made.

When casting a metal about a core, and then drawing the core and thereafter filling up the metal first cast, which has been done, the outer side of the metal first cast is chilled by its contact with the mold, and the inner surface of the said metal is chilled to such an extent while the core is being drawn as to prevent fusion between the metal of the first cast and the metal thereafter poured into it.

25 In accordance with my invention the first or center cast is cooled by the mold only upon its outer surface, leaving the main central body of the first cast unexposed and in a fluid condition, so that the internal heat of the said first cast, the mold being drawn quickly and the second metal being quickly poured into the space left vacant by drawing the inner mold, is sufficient with the heat of the surrounding metal to enable the outer surface of the first

cast, which was uncovered by withdrawing the 50 inner mold, to effect a union with the metal last poured against its external surface.

The inner mold, which holds the first cast, prevents the air from acting upon the surface thereof sufficiently to oxidize the same, and 55 pulling the first mold and pouring the second metal promptly into the space in the outer mold occupied by the inner mold when the first cast was made enables the second cast to be made on the first cast while the latter is yet 60 sufficiently hot, by reason of its internal heat, to effect a fusion at its surface with the surrounding metal of the second cast, thus making a homogeneous ingot composed of two distinct 65 grades of metal or steel.

Figure 1, in vertical section, shows an inner and outer mold constructed in accordance with my invention; Fig. 2, a like view thereof with the inner mold filled with metal for the first cast and the inner mold thereafter partially 70 pulled; Fig. 3, a like view with the second cast poured on the first cast and the outer mold unhooked and separated. Fig. 4 is a top view of Fig. 1. Fig. 5 is a top view of Fig. 3. Fig. 6 is a view of Fig. 2 in the line xx , showing 75 the sand-supports as partially drawn out, and Fig. 7 shows the ingot removed from the molds. In Figs. 4 to 6, inclusive, the dotted line $x^2 x^2$ represents the line of section for Figs. 1 to 3, inclusive.

The compound mold is composed of an outer mold, A, and an inner mold, B, set on a base, C, the said inner and outer molds, as herein represented, being composed of two halves. The halves or parts of the outer mold are 80 joined together by means of fastening devices, shown as hooks a ; but instead thereof I may employ any other usual mold-fastening devices, such as clamps. The inner mold where the edges of its halves meet (see Figs. 1 and 90 4) is grooved, as at h , to receive dry sand to form a fluid-metal-tight joint. The base C is shown as recessed or chambered at c' , and the said recesses or chambers are closed by means of covers c^2 or slides arranged, as shown, opposite the spaces between the inner and outer molds, to support sand, d , or other non-fusible 95 substance which will keep the said molds from

direct contact, but yet permit the inner mold to be drawn from the outer mold without sticking.

With the parts as in Fig. 1, the metal for the first cast will be poured so as to fill that part of the compound mold which is not filled by the inner mold, and to do this the metal first poured meets the base C at the lower end of the inner mold, and the said metal for the first cast thus fills the inner mold, as at f, Fig. 2, where the first cast is marked f. Immediately upon the production of the first cast, and while the same is yet hot, the slides or covers e' are fully drawn out, as represented by but one of the said slides in Fig. 6, thus enabling the column of sand or equivalent material to drop into the recesses or chambers e', (see Figs. 2 and 6,) thus leaving spaces g, so that the inner mold may be easily lifted or pulled from the outer mold without friction one against the other.

Fig. 2 shows the inner mold partially pulled to leave the first cast, f, standing on the plate C, and as soon as the mold B is pulled and before the surface of the same has a chance to oxidize or cool, provided a fusion of the surfaces of the metal of the first cast is desired with the metal of the second cast, the metal for the second cast, s, or shell is poured into the space left in the outer mold, A, by pulling or withdrawing the inner mold, B, from it. The second cast, s, having been made outside the first cast, f, the mold A will be unfastened and separated, as in Figs. 3 and 5, to enable the ingot to be withdrawn; or the outer mold may be entirely removed from the bottom portion, C, leaving the ingot as in Fig. 7, wherein the first cast is marked f, and the second or external cast s.

In practice the kind of metal first to be poured is determined by the character of the ingot desired to be produced. If an ingot with a hard surface and a softer metal center is desired, the first or inner cast is of soft steel or metal and the second or outer cast of a harder steel or metal; but if an ingot with a hard steel or metal center and a softer surface

is desired, then the first or inner cast is made of the hard steel or metal and the second or outer cast of a softer metal.

The ingot first described may be used advantageously for a variety of purposes, among which I will name a railroad-rail.

A rail made from an ingot having a harder surface forms the subject of another application, No. 126,656, filed April 4, 1884, and is therefore not herein claimed.

The molds A B will be composed of metal.

An ingot with a hard center and softer surface is useful for various purposes, among which I will mention armor-plates.

I claim—

1. A compound mold for casting compound ingots, composed of an outer mold and a second removable hollow mold arranged within the outer mold, in order that the first cast may be made in the inner mold, that the inner mold may be then withdrawn, and that the last cast may be made in the space at first occupied by the inner mold, as and for the purpose set forth.

2. The outer mold combined with the inner mold, separated therefrom by a filling of sand or non-fusible material, to enable the inner mold to be readily drawn from the outer mold, substantially as described.

3. The outer and the inner molds separated by a film or layer of sand or non-fusible material, combined with the base-plate provided with recesses or chambers for the reception of the said sand when the inner mold is to be drawn from the outer mold, substantially as described.

4. The hollow laterally-separable outer mold, combined with the hollow removable inner mold, substantially as described.

In testimony whereof I have signed my name to this specification in the presence of two subscribing witnesses.

ELBRIDGE WHEELER.
